ELECTRIC RARE GAS FILLED LAMP

Jean Marie Edouard de Beaufort, Paris, France, and Anton Lederer, Vienna, Austria; Catherine Danzer and General Conrad Randa, executors of said Anton Lederer, deceased, assignors of the entire right of Anton Lederer, deceased, to Ernest Anton Lederer, Glen Ridge, N. J.

Application December 22, 1930, Serial No. 504,138.
In Austria February 22, 1930. Renewed December 21, 1934.

1 Claim. (Cl. 176—122)

Electric rare gas filled lamps as known heretofore are essentially of such construction that the glass vessel containing the filling of rare gas, usually neon or a mixture of neon and helium, is in the form of a tube with the electrodes arranged at the ends thereof. If a sufficiently high voltage is applied to the two electrodes light phenomena appear in the interior of the vessel between the electrodes which light phenomena may be used for illuminating purposes. If the glass vessel contains neon or a mixture of neon and helium the result is a red or orange-red light filling the tubular space between the electrodes; and if some mercury is vaporized within the tube, so that also the vapour of mercury is excited to light a blue light results. In all cases, however, it is the light phenomena appearing in the space between the electrodes, which are made use of for illuminating purposes in such previously known lamps. Such lamps could be operated either on direct or on alternate current and contained either cold or hot electrodes. But heretofore it has been possible only to obtain either red light or blue light, and never both simultaneously. According to the present invention the envelope of the rare gas filled lamp is of such shape and the electrodes are arranged therein in such a manner that not only the light phenomena appearing in the space between the electrodes but also those appearing around the electrode system may develop and be made use of for illuminating purposes. It is of advantage in this connection to reduce the mutual distance of the electrodes as compared to previously known luminous tubes and to shape the lamp vessel in such a way that it surrounds the electrode system, preferably in all directions, at such a distance that light phenomena may develop also outside of the electrode system. The light phenomena appearing in the lamp may then be influenced in a manner never observed before, by proper selection of the relations of pressures of the gases or gas and vapour mixtures of the lamp filling, as well as by a modification of the electric constants which come into consideration for the operation of the lamp so that various effects may be produced.

To enable the invention to be clearly understood one arrangement thereof will now be described by way of example with reference to the single diagrammatic figure of the accompanying drawing.

Within a globe-shaped glass bulb *a* the two electrodes *b* are arranged symmetrically with respect to the centre of the bulb at a comparatively small distance from each other. The electrodes

may consist for example of nickel tubes of about 3 mm. diameter and 25 to 30 mm. length said tubes being provided with an electron emitting coating; through each of these nickel tubes passes a tungsten wire which can be caused to flow by means of an electric current, which wires heat the electrodes to the electron emission temperature. For operation on alternate current both electrodes may be made as above described, whilst for operation on direct current it is sufficient to construct only the cathode in that way. The electrode separation may, for example, be from 5 to 10 mm. and the diameter of the glass globe *a* from 60 to 70 mm.

The gas filling of the glass bulb may consist, for instance, of a mixture of 75% neon and 25% helium and the pressure of this rare gas mixture at room temperature may be approximately within a range of 0.06 to 10 mm. mercury. Furthermore, in the glass bulb *a* a small quantity of mercury is introduced such as in the form of a compound of mercury, as indicated at *d*, such compound being then decomposed so that when the lamp is started, mercury vaporizes and this vapour admixes to the rare gas filling. The average temperature which obtains within the lamp during operation is about 100° to 300° C., and the pressure of the mercury vapour that is formed corresponds to the temperature. Such lamps may be operated on ordinary line voltages or on even lower voltages such as about 20 volts and the discharge current intensity is about 0.4 to 0.5 ampere. Such lamps do not require for operation any such high voltages as have heretofore been customary for electric rare gas filled illuminating lamps.

If a lamp according to the present invention is started, intense red or orange-red lighting "aureoles" are formed around the electrodes the borders of which aureoles are indicated in the drawing in dotted lines *c*, and which, in consequence of the small electrode separation merge into one another to form an almost uniform aureole surrounding the two electrodes. The boundary of this aureole is of course not clearly defined.

The glass globe *a* is spaced from the electrode system at such a distance that light phenomena may develop also in the space outside of the electrode system, and it has been found that these light phenomena outside the electrode system may, as above mentioned, be influenced in such a manner that the two light phenomena have different appearances. Ordinarily the whole space between the aureole *c* and the wall of the glass

bulb *a* gives blue light since it corresponds to the mercury vapour, and there results in this way a light phenomenon showing a blue envelope around an orange-red core becoming somewhat indistinct towards the exterior. The higher the pressure of the rare gas-filling, within the indicated limits, the smaller is the aureole *c* surrounding the electrodes, and with decreasing pressure it expands outwardly whilst the blue halo fills the space between the aureole and the external glass wall, and is consequently pressed outwardly with decreasing pressure and on the other hand its thickness increases towards the electrodes when the aureole is, so to speak, compressed with increasing pressure.

The pressure of the rare gas can be diminished to such an extent that the boundary of the aureole advances to the neighbourhood of the wall of the glass vessel *a* while the light intensity of the aureole decreases accordingly, and it is to be observed that with progressive expansion of the aureole the light phenomena filling the glass vessel *a* become more and more white or nearly white in appearance. The obtaining of a white appearance may be still further improved by the use of a frosted or translucent white glass for the vessel *a* because this tends somewhat to equalize the differences of intensity.

In some cases the inner surface of the glass vessel *a* shows a bluish halo which indicates that the white appearance of the lamp may be due to the fact that the orange-red core-light or aureole has to penetrate a blue envelope before emergence.

A spectroscopic examination of this white light phenomenon shows lines of all colours from the extreme red to the extreme violet, and even ultra-violet rays can be observed if the lamp vessel consists of a material capable of transmitting this kind of rays. The fact that this white light phenomenon is very similar to daylight is confirmed by the substantial preservation of the various natural colours when illuminated by the lamp.

The demarcation between the aureole and the surrounding blue halo may be displaced one way or the other by modification of the electric constants, more particularly of the current intensity, of the size of the electrodes, of the power of emission and of other variables, and in this way lamps with various light effects may be produced, namely lamps with an orange-red core of different size surrounded by a blue halo, or lamps emitting a white light.

The bicolour light phenomenon in such a lamp has its origin in the fact that the conditions for luminous excitation (vibration) of various gases and vapours are different and that the conditions for excitation (density of current) vary with the distance from the electrodes. In the space between the electrodes and in their close proximity there are conditions for excitation which are sufficient to excite the rare gases as well as the mer-

cury vapour to light; the lighting effect of the neon, however, evidently prevails over that of the mercury to such an extent that in the aureole the blue light of the mercury does not appear. At a greater distance from the electrode system the mercury alone is excited to light, and not the rare gas and consequently outside the aureole it is the mercury alone that lights. It is possible, however, as shown above, to modify the conditions for excitation in the interior of the lamp by modification of the relations of pressures and of the electric constants, in such a way that even at greater distances from the electrodes conditions for excitation of the rare gas continue so that an expansion of the rare gas light close to the glass wall takes place and the described phenomenon of white light is obtained.

For obtaining this phenomenon of white light the pressure of the rare gas should be between about 2 to 5 mm. and in any case, however, below 10 mm. mercury.

The rare gas-filling may consist of about from 55% to 99% neon and about from 45% to 1% helium. For lamps in which the bicolour light is desired to be clearly maintained it is advisable to use a comparatively small addition of argon, namely about from $\frac{1}{4}$ to $\frac{1}{5}$ of the mixture of neon and helium.

As far as the construction is concerned the lamp may be modified in various ways from the construction hereinbefore described with reference to the drawing. The mutual distance of the electrodes may be increased so that ultimately each electrode has its own separately visible aureole, and the outer shape of the glass vessel *a* may deviate from the globe shape. What is important however is that the wall of the glass vessel surrounds the electrode system at such a distance that the described light phenomena can develop more or less fully outside the electrode system.

We claim:—

An electric illuminating lamp for operation on alternating current, comprising a globular bulb having a rare gas atmosphere at least containing neon, a small quantity of mercury, and two cooperating electrodes at least one of which is adapted to be indirectly heated to electron emission temperature and is capable of electron emission at relatively low temperature, whereby to produce a luminous gaseous discharge, said electrodes being located symmetrically in the center of the bulb at about 10 mm. apart, said bulb being about 60 to 70 mm. diameter, and the pressure of the contained gas being between about 2 and 10 mm., such that at a voltage of about 20 volts the gaseous discharge current is about 0.4 to 0.5 ampere while the total illumination given by the lamp is due to the simultaneous excitation to luminescence of the rare gas and mercury vapor.
